Des. 224,279
Patented July 11, 1972

224,279

SMOKING APPLIANCE

Jesse L. Nubla, P.O. Box 2556, Manila,
Philippine Republic

Filed Nov. 17, 1970, Ser. No. 26,043

Claims priority, application Philippines July 16, 1970

Term of patent 14 years

Int. Cl. D27—02

U.S. Cl. D85—8

Fig. 1

Fig. 2

Fig. 3

Fig. 4

Fig. 5

FIG. 1 is a side elevational view of a smoking appliance showing my new design, the opposite side being a mirror image of the side shown;

FIG. 2 is an elevational view looking from the right of FIG. 1;

FIG. 3 is an elevational view looking from the left of FIG. 1;

FIG. 4 is a top plan view; and

FIG. 5 is a bottom plan view thereof.

I claim:

The ornamental design for a smoking appliance, as shown and described.
